DOLL WIG PACKAGE

James A. Lint, 336 Grand St.,
Coldwater, Mich. 49036

Filed Feb. 10, 1967, Ser. No. 5,770

Term of patent 14 years

(Cl. D9—191)

FIG. 1

I claim:

The ornamental design for a doll wig package, substantially as shown and described.
